UNITED STATES PATENT OFFICE.

ALBERT L. IDE, OF SPRINGFIELD, ILLINOIS.

VALVE FOR STEAM-ENGINES.

SPECIFICATION forming part of Letters Patent No. 447,490, dated March 3, 1891.

Application filed September 5, 1890. Serial No. 364,046. (No model.)

To all whom it may concern:

Be it known that I, ALBERT L. IDE, a resident of Springfield, in the county of Sangamon and State of Illinois, have invented certain new and useful Improvements in Valves for Steam-Engines; and I do hereby declare that the following is a full, clear, and exact description thereof, reference being had to the accompanying drawings, and to the letters of reference marked thereon, which form a part of this specification.

This invention relates to improvements in valves for steam-engines; and it consists in the matters hereinafter described, and pointed out in the claims.

In the accompanying drawings, Figure 1 is a horizontal longitudinal section of a steam-chest provided with a slide-valve embodying my invention. Fig. 2 is a cross-section of the same on line 2 2, Fig. 1. Fig. 3 is a vertical section on line 3 3 of Fig. 2. Fig. 4 is a detail side elevation of the slide-valve. Fig. 5 is an enlarged detail section showing the valve in a changed position from that shown in Fig. 1. Fig. 6 is a similar section showing still another position of the valve. Fig. 7 is a similar view illustrating a modified form of valve.

In said drawings, A indicates the engine-cylinder, B the steam-chest, and B' the steam-supply pipe.

C indicates the valve-seat, provided with steam-ports c c', communicating with the opposite ends of the cylinder A and provided with a central exhaust-port c².

D indicates the slide-valve, D' the valve-stem connected therewith, and E a valve-plate arranged upon the side of said valve D opposite to the valve-seat C and parallel therewith.

As shown in said drawings, the slide-valve D is generally of flat or gridiron form, as shown more particularly in Figs. 3 and 4, and consists of two parallel side pieces d d, two end cross-bars d' d', and two intermediate cross-bars d² d². As a detail of construction in the particular valve shown, said valve is provided with a central tubular part D², through which passes the valve-stem D', said tubular part affording a brace to connect the cross-bars of the valve, and thereby give strength and rigidity to the same.

The valve D, made as above described, is located in contact with the valve-seat C, and operates in connection therewith and also with the stationary valve-plate E, which is sustained within the steam-chest opposite to the valve-seat C, and is provided with a flat bearing-surface E', which is in contact with the outer side of the valve D. The valve-plate E is conveniently held in position by means of inwardly-projecting flanges ee, which rest at their inner edges against the valve-seat C at opposite sides or edges of the valve D, as shown more particularly in Fig. 2, said valve-plate E being arranged to bear at its side edges against the side walls of the steam-chest, whereby the said valve-plate is held from shifting sidewise, as clearly shown in the drawings. A pin or stud e', Fig. 2, is inserted in the valve-seat C, and enters a recess in the flange e of the valve-plate, to hold the latter from shifting endwise or longitudinally.

E² is a spring interposed between the outer wall or cover of the steam-chest and the valve-plate E, to hold the latter in operative position. The spring E² does not act against steam-pressure in holding the valve-plate against the valve-seat C, inasmuch as the steam-pressure comes outside of said valve-plate and tends to press the same against the valve-seat. Said spring E² enables the valve-plate to yield outwardly, so as to relieve the parts from strain in case of an accumulation of water in the cylinder, thereby avoiding danger of breakage of the parts by the compression of the water in either end of the cylinder at such time. The valve-plate E is made shorter than the length of the steam-chest, and the end or outer cross-bars d' d² of the valve E are arranged at such distance apart, and the valve is moved through such distance that said cross-bars are carried alternately past the ends of the valve-plate or outwardly from beneath the same, so as to admit steam from the steam-chest between the valve-plate and the valve-seat to the steam-ports c c'. The inner or intermediate cross-bars d² d² of the valve are arranged at such distance apart that they are moved alternately away from the surface of the valve-seat to a point opposite the exhaust-port c², thereby leaving open the space between the

valve-seat and the valve-plate for the passage of steam from one of the steam-ports $c c'$ to the exhaust-port c^2 .

In order that steam may enter at both sides 5 or edges of the end cross-bars of the valve when the latter are moved outwardly past the end of the valve-plate, as above described, the valve-seat C is made of the same length as the valve-plate, so that spaces are left between the ends of the valve-seat and the ends 10 of the steam-chest, and the parts of the wall of the steam-chest adjacent to the ends of the valve-seat are recessed, or, in other words, the valve-seat is elevated above the adjacent parts of the wall of the steam-chest. This 15 construction enables the steam to pass around the said end cross-bars, thereby affording a steam-passage of twice the area, with the same movement of the valve as is afforded in case the steam enters at one side only of 20 said cross-bar. For a similar purpose the valve-plate E is provided with a central recess e^2 of the same length and width as the exhaust-port c^2 and arranged opposite the latter. Said recess allows the exhaust-steam to 25 pass around on both sides of the inner cross-bars $d^3 d^4$ in its passage from the ports $c c'$ to the exhaust-port c^2 , thereby affording a large area for the exit of steam with a small 30 movement of the valve.

The valve-plate E is herein shown as provided on its inner or bearing surface near its ends with two transversely-arranged recesses $e^3 e^4$, made of the same length and width as 35 the steam-ports $c c'$ and located opposite the latter. By the presence of said recesses in the bearing-surface of the valve-plate the latter is made to correspond exactly with the bearing-surface of the valve-seat, thus insuring 40 an equal steam-pressure on opposite sides of the valve and the perfect balancing of the latter.

As a separate and further improvement, the valve-plate E is provided with a steam-passage E^3 , extending longitudinally through 45 the body of said plate and opening at its ends through the inner or bearing surface of the plate near the ends of the latter. The said passage E^3 is designed to afford an additional 50 area of passage for the inflow of steam to the cylinder-ports, and for this purpose its ends are so located with reference to the ends of the valve-plate that when the cross-bar at one end of slide-valve begins to leave the edge of 55 said plate the cross-bar at the opposite end of the valve will begin to pass from over the end of said passage, thereby admitting steam through said passage to the ports $c c'$ at the same time that steam is admitted to said 60 steam-port around the edges of the outwardly-moving cross-bar of the valve.

The operation of the valve will be more clearly understood by reference to Figs. 1, 5, and 6.

65 As illustrated in Fig. 1, the valve D is in position for the passage of live steam through the port c' to the cylinder A. At this time

the cross-bar d^2 of the valve D stands outside of and free from the valve-seat C and the valve-plate E, so that steam is free to pass from the steam-chest around both sides of said bar d^2 to the space between said valve-plate E and the valve-seat C and into the port C' , as before described. At this time the intermediate cross-bar d^4 nearest the cross-bar d^2 stands between the steam-port c' and the exhaust-port c^2 , thus closing the space between said ports, while the external cross-bar d' at the opposite end of the valve stands between the port c and the end of the valve-seat, thus closing the space between the said valve-seat and the valve-plate E at this point. Exhaust-steam is at this time free to pass from the said port c to the exhaust-port c^2 through the space between the valve-plate and the valve-seat, the cross-bar d^3 at this time being located opposite the exhaust-port and in position to allow the free passage of steam around both sides of said bar into said port.

Fig. 5 shows the valve at the limit of its 90 stroke opposite to that shown in Fig. 1, live steam at this time passing through the port c to the cylinder, the exhaust passing through port c' to the exhaust-port c^2 in the manner illustrated.

Fig. 6 illustrates an intermediate position of the parts when the valve is being shifted from the position shown in Fig. 5 to that shown in Fig. 1. This figure shows the exhaust-port as already partially opened to allow the passage of exhaust-steam from the port c to the exhaust-port c^2 by the movement of the intermediate cross-bar d^3 from contact with the valve-seat C and the bearing-surface E' in that part of the same between the steam-port c and the exhaust-port c^2 , thereby allowing steam to pass around both sides of the bar d^3 to the exhaust-port. Admission of steam will begin as soon as the cross-bar d^2 passes from between the surfaces of the valve-seat and the valve-plate.

The passage E^3 in the valve-plate E affords an additional or increased area for the passage of live steam to the cylinder during the opening of the steam-ports, the ports or openings in the face of the valve-plate E at the ends of said passage being so arranged that one of the end cross-bars, as d' , will begin to uncover said passage at one end of the valve at the same time that the cross-bar d^2 120 at the opposite end of the valve begins to leave the edges of the valve-seat and the valve-plate. This is shown in Fig. 6 of the drawings, from which it will be clearly seen that a slight further movement of the valve 125 D toward the right hand will bring the cross-bar d' past the edge of the opening of the passage E^3 at the same time that the inner margins of the cross-bar d^2 pass beyond the edges of the valve-plate and the valve-seat. 130 It will of course be seen that one end of the passage E^3 is always in communication with the steam-port into which live steam is about to be admitted when the other end of said

passage is being opened for the admission of steam from the steam-chest. This passage being of considerably less width than the opening afforded by the cross-bar d or d' when the valve is at either limit of its throw, said passage will commonly be of use only when the engine is working at short stroke, it being obvious that when the valve is moved throughout the full length of its stroke, or nearly so, the steam-inlet space afforded between each cross-bar d' or d^2 and the adjacent ends of the valve-plate and the valve-seat will be as great or greater than required to admit all the steam that can pass through the steam-ports.

It will of course be understood that the desired area for the admission of steam to the cylinder may be provided without employing the passage E^3 by making the valve D of sufficient width for the purpose; but for compactness of construction and to avoid the objectionable features which would be connected with a very broad valve said passage is employed.

I am aware that valve-plates have been heretofore employed, the same being arranged parallel with the surface of the valve-seat and the valve being arranged to move between the surface of said plate and the seat; but in all these prior forms of construction the valve-plates have been provided with perforations or ports extending through them from face to face, through which steam passes to the valve when the ports in the valve coincide with those in the valve-plate. It is obvious that in this form of construction the advantage of increased area for the admission of steam such as is provided for in my improved form of construction is entirely absent.

The valve D (shown in the accompanying drawings) is arranged vertically, the steam-chest being placed at one side of the cylinder, so that the weight of said valve comes entirely upon the lower edge thereof.

As a further and separate improvement applicable to valves of this character when arranged in the manner shown, I place between the lower edge of the valve and the supporting-surface of the steam-chest adjacent to it one or more anti-friction rollers, which sustain the weight of the valve, and thereby avoid the frictional resistance which would result from the sliding contact of the lower edge of the valve with the surface by which the same is sustained. As illustrated in the accompanying drawings, two anti-friction rollers F are employed, said rollers being located in notches or recesses f , formed in the lower flange e of the valve E , so that the rollers rest upon the bottom wall of the steam-chest. In this construction the rollers are conveniently made of the same diameter as the thickness of the flange e . The rollers F (shown in the drawings) are of cylindric form and are made of such length that their flat end faces come flush with the side faces

of the valve D . This particular construction is not, however, essential, and the rollers employed may be of spherical instead of cylindric form, and the bearing-surfaces therefor may be arranged otherwise than in the manner described.

I am aware that rollers have been heretofore employed in connection with slide-valves, said rollers being arranged between the bearing-face of the valve and its seat and adapted to prevent friction between said surfaces or being arranged upon the surface of the valve opposite or remote from the seat and adapted to take the "lift" of the steam and prevent the valve from being raised from its seat. By my improved construction, however, the valve is entirely balanced, and there is no necessity for rollers or other anti-friction devices between the bearing-surfaces; but the valve being arranged vertically and its weight being supported entirely upon its narrow lower edge, I provide the rollers, as shown, to prevent the friction between the support for the valve and the lower edge of the valve, which arises from the use of a relatively large and heavy valve having a narrow bearing-edge.

Some of the features of the valve shown may be used with advantage without other features shown and described, it being obvious that under some circumstances the reduction in first cost of the engine or cheapness of fuel will warrant the omission of some of the novel features herein shown, even at a loss of the advantages gained by the presence of such features—as, for instance, the construction of the valve-plate shown in Fig. 7 may be used, in which said valve-plate is formed without the passage E^3 .

In the flat valve D shown in Fig. 7 the advantage of a double admission of steam is obtained—that is to say, a relatively large opening for the passage of the steam is afforded by a short movement of the valve; but this favorable result is obtained to a greater degree when the passage E^3 in the valve-plate is employed, such passage obviously affording a triple instead of a double opening for the admission of steam without increasing the stroke of the valve, with obvious advantages in steam economy and consequent saving of fuel.

The flat gridiron or barred valve, combined with a valve-seat and imperforate valve-plate, as herein described, may obviously be used either in single-acting engines or by being combined with another valve of any desired form of construction may be adapted for use in a compound engine.

The valve construction herein described and shown is the same as that illustrated in another application filed by me on June 10, 1890, Serial No. 354,927, for improvements in "compound engines."

I claim as my invention—

1. The combination, with an engine-cylinder and a stationary chest having a valve-seat provided with steam-ports near its ends

and a central exhaust-port, of a flat reciprocating valve provided with four transverse parallel bars and a stationary imperforate valve-plate arranged parallel with the valve-seat, said valve-seat being made shorter than the steam-chest and the outer cross-bars of the valve being located at such distance apart that at each limit of the movement of the valve the cross-bar at one end of the valve will stand outside of or beyond the said plate, so as to admit steam from the chest to the adjacent steam-port, while the cross-bar at the opposite end of the valve will stand between the end of the plate and the adjacent steam-port, so as to cut off the flow of steam to the latter, substantially as described.

2. The combination, with an engine-cylinder and a steam-chest provided with a valve-seat having steam-ports near its ends and a central exhaust-port, of a flat valve provided with four transverse parallel bars and an imperforate valve-plate arranged parallel with the valve-seat, said valve-plate and the valve-seat being made shorter than the interior of

the steam-chest, and the valve-seat being raised at its ends above the adjacent wall of the steam-chest, and the exterior cross-bars of the valve being disposed at such distance apart that at each limit of the movement of the valve the cross-bar at one end of the valve will stand outside of or beyond the said plate, so as to admit steam from the chest to the adjacent steam-port, while the cross-bar at the opposite end of the valve will stand between the end of the plate and the adjacent steam-port, so as to cut off the flow of steam to the latter, the said valve-plate being provided with a longitudinal passage opening at its ends at the inner or bearing face of the plate adjacent to the ends thereof, substantially as described.

In testimony that I claim the foregoing as my invention I affix my signature in presence of two witnesses.

ALBERT L. IDE.
